EMBROIDERING-MACHINE.

1,266,083.

Specification of Letters Patent.

Patented May 14, 1918.

Application filed January 19, 1916. Serial No. 73,060.

To all whom it may concern:

Be it known that we, PAUL TITTES and WILHELM SCHÖNHERR, subjects of the German Emperor, residing at Plauen, in Vogtland, in the Kingdom of Saxony, Germany, have invented certain new and useful Improvements in Embroidering-Machines, of which the following is a specification.

The operation of shuttle embroidering machines is essentially the same as that of ordinary shuttle sewing machines, namely the needle pierces the fabric, the needle thread by a short retreat of the needle forms a loop under or behind the fabric, and while the shuttle is passing through the said loop the needle thread is slackened to permit the spacious shuttle to entirely slip through the loop. But as soon as the rear end of the shuttle has passed the loop, the slackened thread, while the needle retreats, must be quickly taken up. After the adjustment of the fabric for the next stitch, when the needle point again touches the fabric, the thread is slightly tensioned in order to tighten the formed stitch and to simultaneously draw off so much thread from the thread roller as corresponds to the particular length of stitch or the extent of the linear displacement of the tambour frame.

From the above it is clear what importance the thread take-up mechanism plays. Such mechanism must be constructed with great exactness so as to operate with precision and a correctly apportioned force, for otherwise fine embroidery can never be produced.

The technical problem involved is rendered more difficult nowadays, when apart from the needle thread, a second, sometimes very thick thread or cord, is sewed onto the embroidery, either as an ornamental cord or as a filling to form a protruding part or relief of the design such, for instance, as leaves or the like.

Because of the limited space on the machine, the provisions of a double set of the hitherto used take-up mechanisms, one for the ordinary needle thread and the other for the second thread or cord, would be very impracticable. But apart from that, the second thread must be handled and laid on the fabric in front of the needle with particular care, especially when, as is more often the case, the second thread is used as ornamental cord. This second thread, in a greater measure than the ordinary thread, being apt to

curl and form knots, must never be allowed to remain slack and hang down, but on the contrary, must be always maintained at a uniform and gentle tension.

To accomplish this effect and to obviate the drawbacks of the hitherto used structures, is the object of the present invention, according to which the second thread or cord is slackened and taken up always to the same extent by means of a roller which for all stitches is positively oscillated uniformly and the variable amount of thread required for the particular length of stitch and determined by the linear displacement of the tambour frame is obtained by freeing the said roller for just a moment while the thread is still held under gentle tension. In this manner the thread is given no opportunity whatsoever to ever curl, for even during the moment when the roller is free, the thread is maintained under tension without which, obviously, the feeding of the necessary amount of thread for the length of the stitch is impossible.

One embodiment of our invention is illustrated more or less diagrammatically in the accompanying drawing in which similar reference characters denote corresponding parts and in which Figure 1 is a sectional side view of an embroidering machine equipped with our new mechanism; Fig. 2 is an enlarged detail of our new mechanism and Fig. 3 is a sectional front view of the detail shown in Fig. 2.

In the drawing the tambour frame and fabric are indicated by line $x-x$ in Fig. 1. Projecting from the casting or frame 1 of the machine are supports 2 and 3 for the different mechanisms. 4 is the main driving shaft from which by well known transmission means (not shown) motion is imparted to the different mechanisms, as for instance to the needle shaft 5 which reciprocates the bars 7 uniformly arranged in a horizontal row over the entire length of the machine and of which only one is shown in the drawing. Each bar 7 is provided with an arm 8 carrying the stitching needle 9. 10 and 11 are the well known take-up wires carried by the levers 12 and 13 respectively, and over which is wound the needle thread y leading from its respective spool 14 and passing over the emery roller 15.

For each needle there is a presser foot 17 and for each ornamental or filling thread z 110

a guide 21 of well known construction, which serves to lay the thread z on the fabric in accordance with a predetermined design. These presser feet 17 are fixed on a shaft 16. Each guide 21 is arranged on the end of a bar 20 which is guided by swinging levers 18 and 19 fixed respectively on the shafts 16 and 19' which receive short oscillatory motions from the driving shaft 10 by suitable means (not shown).

Thus far the construction is old.

The feature constituting our invention is the following:

Each thread z coming from its respective spool 26 is conveyed to the respective guide 21 around a rigid rail 25, thence in contact with a thread feeler or tensioning wire 24, thence once around a roller 23, and thence over a taut wire 22. 15 The thread roller 23, in order to offer gentle resistance to the thread z need not, as the roller 15, be provided with an emery layer, but may be only covered, according to the nature of the thread with cloth, plush or velvet, as 23'. In a similar manner the rail 25 may receive a covering 25' of cloth or the like.

On the shaft or spindle 27 of the roller 23 are fixed two ratchet wheels 28, 29 with 30 which respectively coöperate pawls 30, 31 pivoted on a common double armed lever 32 having its fulcrum on the spindle 27. When the lever 32 by means of a rod 33 is oscillated, the roller 23 by the pawls 30 and 31 35 will be caused to turn to and fro with equal degrees in both directions, indicated by the arrows u and v . The lever 32 is oscillated by means of a cam 35 which coöperates with a roll 34 rotatively fixed on the rod 33 and 40 which is held in contact with the circumference of the cam by a spring 36 fixed at one end at 32' to one of the arms of the double armed lever 32 and at the other end, at 3', to the bracket 3. The rod 33 is pivotally connected, at 33', to the lever 32. The cam 35, as shown, is in form of a circular disk arranged eccentrically on the driving shaft 4, thereby imparting to the lever 32 uniform oscillatory movement. If other 45 movements were desired, as for instance, when the mechanism is applied for the thread y , the cam 35 may receive a different configuration.

The dog 31 is extended beyond its fulcrum to form a thumb 37 which at the extreme end of the upper stroke of the lever 32 will be caused to strike against a projection or nose 38 of the frame, and thereby during the short period of contact between the parts 37 and 38 cause the dog 31 to free 50 the roller 23. It is just during that short interval that the thread z finds opportunity to follow the displacement of the tambour frame to the amount required for the particular length of stitch.

To obtain a very sensitive action of the pawls or dogs a double set thereof may be provided, as seen at 30, 30', 31, 31' (Fig. 3), in order that their points engaging the teeth of the wheels may, in well known manner, 70 be displaced half a pitch relatively to each other. This amounts to the same as reducing the pitch of the teeth of the two wheels 28, 29 to one half.

The tension wire 24 is carried by small levers 39' which freely swing on the spindle 39 and which are actuated by springs 40 having the tendency to draw them to the right.

The mode of operation is as follows:

The thread coming from the spool 26 and guided in the aforescribed manner toward the guides 21 is, in accordance with the operations of the guides 21 and the needles 9, periodically slackened and taken up to the same amount, owing to the oscillatory movement imparted to the roller 23 by the pawls 30, 31. But at a certain moment the thumb 37 strikes against the nose 38 and only for the moment of contact between the parts 37 and 38 the pawl 31 releases the roller 23 in consequence of which the latter by the pull of the thread z may freely turn in the direction indicated by the arrow v in Figs. 1 and 2.

When the lever 32 swings downwardly the pawl 31, owing to the turn made by the roller 23, will engage the wheel 29 a few teeth below its former engagement, so that the thread unwound from the spool will not 100 be subsequently taken up to the full amount. This amount of thread, which remains slack, is just that which is required by the linear displacement of the tambour frame to produce the desired length of stitch.

The piece of thread extending between the roller 23 and the tension wire 24 which in consequence of the free turn made by the roller 23 is slackened will be instantaneously tensioned by the wire 24 which will be carried from position a to b by the action of the springs 40 on the lever 39'.

Since the construction may be variously modified without departing from the principle of our invention, we do not wish to restrict ourselves to the details shown and described.

What we claim and desire to secure by Letters Patent is:

1. In a shuttle embroidering machine, a 120 thread slackening and take-up device, comprising a positively and uniformly oscillated roller over which the thread is wound and means to relieve the said roller for a short interval to allow it to turn freely to furnish 125 the amount of thread required by the linear displacement of the tambour frame.

2. In a shuttle embroidering machine, a 130 thread slackening and take-up device consisting of a positively and uniformly oscil-

lated roller over which the thread is wound, means to relieve the roller for a short interval and a thread tensioning device for constantly holding the thread on the said roller under tension.

3. In a shuttle embroidering machine, the combination with a spool, of a thread slackening and take-up device consisting of a positively and uniformly oscillated roller over which the thread is wound, means to relieve the said roller for a short interval, a rigid guide and a yielding guide, both said guides being interposed between said spool and the said roller and serving to constantly hold the thread on said roller under substantially uniform tension.

4. In a shuttle embroidering machine, a thread slackening and take-up device consisting of a roller over which the thread is guided, means for positively oscillating said roller equally in opposite directions and means for relieving said roller for a short interval to allow it to turn freely and furnish the amount of thread required by the linear displacement of the tambour frame.

5. In a shuttle embroidering machine, a thread slackening and take-up device, consisting of a roller over which the thread is guided, ratchet wheels connected to said roller, sets of oscillating pawls coöperating with said ratchet wheels and adapted to positively actuate said roller imparting to it uniform oscillatory motions and means whereby for a short interval the said roller is relieved and enabled to turn freely to furnish the amount of thread required by the linear displacement of the tambour frame.

6. In a shuttle embroidering machine, a thread slackening and take-up device com-

prising a roller over which the thread is guided, ratchet wheels connected to said roller, sets of oscillating pawls coöperating with said ratchet wheels and adapted to positively and uniformly oscillate said roller, a stop and means on one of said pawls adapted at a certain moment to be actuated by said stop so as to relieve the said roller and to allow it to turn freely so as to furnish the amount of thread required by the linear displacement of the tambour-frame.

7. In a shuttle embroidering machine, a thread slackening and take-up device consisting of a positively and uniformly oscillated roller, means for relieving said roller for a short interval to allow it to turn freely and to furnish the amount of thread required by the linear displacement of the tambour frame and a thread tensioning device which is adapted to constantly engage the thread and which is adapted to constantly hold the thread under tension.

8. In a shuttle embroidering machine, a thread slackening and take-up device, consisting of a positively and uniformly oscillated roller, means for relieving said roller for a short interval to allow it to turn freely, a thread tensioning device and a thread guide, said roller and guide having both a covering of soft material constituting a resistance for the thread.

In testimony whereof we affix our signatures in presence of two witnesses.
